ROBERT EUGENE REDDING, OF MARION, ALABAMA.

MAIL-BAG LOCK.

No. 866,965.

Specification of Letters Patent.

Patented Sept. 24, 1907.

Application filed May 25, 1907. Serial No. 375,821.

To all whom it may concern:

Be it known that I, ROBERT E. REDDING, a citizen of the United States, and a resident of Marion, in the county of Perry and State of Alabama, have invented a new and Improved Mail-Bag Lock, of which the following is a full, clear, and exact description.

The purpose of this invention is to provide a lock having novel features of construction, which adapt it for a locked engagement with a constricting strap passed closely around the closed neck of a mail bag or pouch, and thus prevent access to the contents of the receptacle until the lock is opened with a suitable key.

The invention consists in the novel construction and combination of parts, as is hereinafter described and defined in the subjoined claims.

Reference is to be had to the accompanying drawings forming a part of this specification, in which similar characters of reference indicate corresponding parts in all the views.

20 Figure 1 is a perspective view of the neck portion of a mail bag, and of the improved lock applied upon an encircling strap that is employed for holding the neck of the bag closed when the strap is drawn so as to foldably contract said neck; Fig. 2 is a plan view of the lock, 25 having a side wall thereof removed and the key-post shown in transverse section, other details of the lock being shown as they appear when the locking bolts thereof are retracted and held in such condition; Fig. 3 is a longitudinal sectional plan view, substantially on 30 the line 3—3 in Fig. 4; Fig. 4 is a longitudinal sectional side view, taken at a right angle to the plane of the section shown in Fig. 3, and substantially on the line 4—4 in said figure; Fig. 5 is a side view of a portion of the constriction strap, showing a locking aperture therein 35 and a facing plate secured upon the strap and having a corresponding opening registering with the aperture in the strap; and Fig. 6 is a side view of the key employed as an adjunct of the lock, for working its mechanism to lock and unlock the same.

40 The improvement is applicable upon different sizes of mail bags or pouches that are closed by a drawn strap, 10 in Fig. 1 indicating the mouth portion of such a receptacle for mail matter. Upon the bag 10, at a suitable distance from the free edge of its mouth, a preferably flat strap 11 is held loosely by keeper-loops 12, secured on the exterior of the bag at its neck.

The lock which embodies the features of novelty and which in service is mounted upon the strap 11, comprises the following details: 13 indicates the body 50 portion of the lock, and as shown, consists of a block, preferably constructed of metal, having an oblong rectangular shape and of proper dimensions for effective service. An oblong recess or chamber *a* is formed in the body 13, extending for a suitable depth to a 55 flat bottom and having sufficient capacity to receive the working parts. To adapt the lock body 13 for a

slidable engagement with the strap 11, two similar slots *a'*, of equal depth, are formed longitudinally in and through the ends of said body, essentially parallel with the side walls of the recess *a*, and as shown in Fig. 4, a cap plate 13^a is provided for closing the open side of the lock body, said plate also covering the lateral openings in the slots, thus converting said slots into longitudinal passages through the lock body or casing 13. In one side wall of the chamber *a* near each end 60 thereof, shallow recesses *b*, *b'* are formed, said recesses terminating in shoulders *b*², and the side walls of the recesses are preferably rendered parallel with the opposite side wall of the chamber *a*. At a suitable distance apart, two lateral slots *c*, *c'* are formed in the side walls 65 of the chamber *a*, one slot *c'* extending into the recess *b'*, that is adjacent to an end wall of said chamber, as is clearly shown in Fig. 3. Opposite the slots *c*, *c'*, corresponding recesses *c*² are formed in the outer defining side walls of the respective passages *a'*, said recesses *c*² forming locking shoulders for engagement with the ends of two nearly similar slide bolts 14, 14^a which are details of the lock mechanism. Each slide bolt 14, 14^a, consists of a metal block, the body portion of which is mainly rectangular and from which projects a latch limb *d*, having such form and dimensions as adapts each of said latch limbs to slide freely in a respective slot *c*, *c'* and recess *c*² opposite the same. A guide rod *e* is provided for each slide bolt 14, and as shown in Fig. 3 these rods have their ends loosely engaged in opposite perforations formed in the ends of the bolt bodies and the respective opposite side walls of the chamber *a*. Upon each guide rod *e* a coiled spring *e'* is mounted, and presses upon the slide bolt with which said rod is engaged, thus normally pressing 70 the nose of a respective latch limb *d* outward. Between the shoulders *b*² before mentioned, the intermediate portion of the side wall of the chamber *a* is undercut, forming a channel, and the lower side of the slide bolt 14^a is cut away at the end thereof adjacent to this 75 undercut formation. A detent block is an essential detail, and consists of a yoke piece having two spaced limbs *g*, *g'* that are flat formations having parallel outer side edges and seated on the bottom of the chamber *a*. The limb *g'* works loosely in the undercut channel 80 formed in the side wall of the chamber *a* between the shoulders *b*². A shoulder *d'* is formed at the junction of each latch limb *d* with the body 14 or 14^a of a respective slide bolt of which it is a part, and the yoke limbs *g*, *g'* are so proportioned in length that they will engage 85 with an adjacent shoulder when the latch limbs are retracted against stress of the springs *e'*, and the detent block is pressed toward the latch bolts. The detent block is further formed with an upright rectangular member 15 which is integral with the yoke, and the limbs *g*, *g'* practically extend from the opposite sides 90 of said member 15 of the detent block. In the cap 95

plate 13^a a key-hole *s*² is formed and also opposite the detent block 15 a rectangular opening *h* is formed, and from the top of said detent block a tongue *i* projects up into the opening *h* as is clearly shown in Fig. 4. 5 In the detent block 15 a guide rod *m* is loosely inserted at one end thereof, the opposite end of the guide rod passing through a recess *n* in the end wall of the lock body and thence into a socket that receives and supports said end of the guide rod. Upon the 10 rod *m* a coiled spring *m'* is placed that exerts pressure upon the detent block, and causes the ends of the limbs *g*, *g'* of the detent block to interlock with the shoulders *b*² when the slide bolts 14, 14^a are simultaneously retracted, so as to dispose said working parts 15 of the lock as shown clearly in Fig. 2. Centrally between the slide bolts 14, 14^a, a key-post *o* is erected from the bottom wall of the chamber *a*, and opposite said key-post notches *o'* are formed in the adjacent sides of the slide bolt bodies 14, 14^a. The notches *o'* 20 are preferably formed as arcs of a circle having the key-post *o* as a center, said arcs each terminating in a shoulder *o*² as shown in Figs. 2 and 3. A key 16 is employed as means for working the lock mechanism, and as shown in Fig. 6 has two bits *p*, *p*, projected oppositely from the body of the key, that is hollow and fits loosely upon the key post *o* as indicated by dotted lines in Fig. 3.

As will be seen by reference to Fig. 3, on the rotation of the key 16 in the direction of the curved arrow, the 30 bits *p* will contact with the shoulders *o*² and retract the slide bolts 14, 14^a at the same time.

In the constricting strap 11 at proper points oblong perforations *r* are formed, that are disposed in the two runs of the strap so as to receive the nose of the latch 35 limbs *d* when these members of the strap are drawn tightly around the closed neck of the mail bag, the bolts 14, 14^a then moving toward the sides of the lock body under stress of the spring *e'*. The ends of the latch limbs *d* are sloped transversely so as to form inclines thereon, as shown best in Fig. 3, this construction 40 facilitating the passage of the noses of the latch limbs through the openings in the runs of the strap 11. To permit the operation of the key 16 for unlocking the lock, it is necessary that the tongue *i* be pushed 45 away from the bolt 14^a, which will release the bolts 14, 14^a, from the ends of the locking limbs *g*, *g'*, so that they will assume the position shown in Fig. 3. The key 16 is then inserted and turned in the direction of the curved arrow in Fig. 3, which will cause 50 the bits of the key to impinge upon the shoulders *o*², and draw the latch limbs *d* out of the perforations *r* in the strap member 11. When the bolts 14, 14^a are fully retracted, the detent block 15, will be slid by its spring *m'* toward the latch limbs *d*, *d*, and the toes on the 55 limbs *g*, *g'* of the detent block will interlock with the shoulders *d*', which engagement will adapt the limbs *g*, *g'* to hold the latch limbs *d* retracted, and out of engagement with the strap 11. The perforations *r* in the strap members may be protected from wear by 60 curing thin plates *s* thereon over the perforations *r*

and having similar openings *s'* therein, the openings in the plates permitting the free insertion of the latch bolt limbs *d* therethrough and into the recesses in the side walls of the passages *a'*, and preventing undue wear or strain being imposed upon the strap. The 65 key 16 is of extremely simple form, and is merely shown to illustrate the operation of the lock, and it is to be understood that the form of the key and key-hole in the lock body, may be changed to make the lock more secure. 70

It is to be understood that when the mechanism is placed in the lock body, the cap plate 13^a is to be secured firmly in place by rivets, that may occupy the perforations shown in Fig. 2, and thus prevent access to the interior of the lock body or case. 75

Having thus described my invention, I claim as new, and desire to secure by Letters Patent:

1. A lock, comprising a hollow body or casing, two spring-pressed latch bolts disposed transversely in the casing and having latching limbs that work in opposite 80 side walls of the casing, means to simultaneously retract the latch bolts, and means for releasably holding said latch bolts retracted.

2. A lock, comprising a hollow body or casing, two spring-pressed latch bolts having latch limbs that work 85 through opposite walls of the casing, means for simultaneously retracting the latch bolts, and spring-pressed releasable means for holding the bolts retracted.

3. A lock, comprising an oblong hollow body or casing 90 having parallel sides and also having two longitudinal passages therein, one near each side wall, two spring-pressed oppositely trending slide bolts having latch limbs that work through the inner sides of the casing into the passages, means for simultaneously retracting the slide bolts, and spring-pressed means for releasably holding said 95 bolts retracted.

4. A lock, comprising an oblong hollow body or casing 100 having parallel sides, and also having two longitudinal passages therein, one near each side wall, two spring-pressed slide bolts having latch limbs and disposed transversely in the casing, said latch limbs working in openings in the inner walls of the passages and projecting into said passages, the bolts being simultaneously retractable with a suitable key, and a spring-pressed detent block having limbs adapted for releasably holding the slide bolts retracted. 105

5. In a mail bag lock, the combination with a bag, and a constricting strap thereon having locking apertures therein, of a lock comprising an oblong rectangular hollow body or casing, said casing having two longitudinal passages therethrough near opposite sides, the two runs of the strap occupying these passages and adapted to slide therein, two spring-pressed slide bolts having latch limbs and disposed transversely in the casing, said latch limbs working in openings in the inner walls of the passages, and entering recesses in the outer walls thereof after passing through apertures in the runs of the strap, the bolts being retracted simultaneously by means of a key, a spring-pressed detent block having limbs adapted to engage shoulders on the latch bolts for holding them retracted and thus releasing the strap, and a tongue on the detent block projecting through an opening in a cap plate on the lock casing and which by sliding manipulation will release the slide bolts. 110

In testimony whereof I have signed my name to this 125 specification in the presence of two subscribing witnesses.
